United States Patent Office

Des. 174,823

Patented May 24, 1955

174,823

HANDBAG OR SIMILAR ARTICLE

Helen Macy, New York, N. Y.

Application July 8, 1954, Serial No. 31,339

Term of patent 14 years

(Cl. D87—3)

FIG. 1

FIG. 2

To all whom it may concern:

Be it known that I, Helen Macy, a citizen of the United States of America, residing at the city, county, and State of New York, have invented a new, original, and ornamental Design for a Handbag or Similar Article, of which the following is a specification, reference being had to the accompanying drawing, forming part thereof.

Fig. 1 is a front elevational view of a handbag showing my new design;

Fig. 2 is a rear view thereof with the flap turned up;

Fig. 3 is an edge view thereof; and

Fig. 4 is a perspective view thereof with the front flap in open position.

I claim:

The ornamental design for a handbag or similar article, substantially as shown.
